(57) **CLAIM**

The ornamental design for a surgical apparatus for minimally invasive surgical procedures, substantially as shown and described.

DESCRIPTION

FIG. 1 is a perspective view of a first embodiment of a surgical apparatus for minimally invasive surgical procedures;

FIG. 2 is a front elevation view of the surgical apparatus of FIG. 1;

FIG. 3 is a rear elevation view of the surgical apparatus of FIGS. 1 and 2;

FIG. 4 is a first side elevation view of the surgical apparatus of FIGS. 1-3;

FIG. 5 is a second side elevation view of the surgical apparatus of FIGS. 1-4;

FIG. 6 is a bottom plan view of the surgical apparatus of FIGS. 1-5;

FIG. 7 is a top plan view of the surgical apparatus of FIGS. 1-6;

FIG. 8 is a perspective view of a second embodiment of a surgical apparatus for minimally invasive surgical procedures;

FIG. 9 is a front elevation view of the surgical apparatus of FIG. 8;

FIG. 10 is a rear elevation view of the surgical apparatus of FIGS. 8 and 9;

FIG. 11 is a first side elevation view of the surgical apparatus of FIGS. 8-10;

(Continued)

FIG. 12 is a second side elevation view of the surgical apparatus of FIGS. 8-11;

FIG. 13 is a bottom plan view of the surgical apparatus of FIGS. 8-12; and,

FIG. 14 is a top plan view of the surgical apparatus of FIGS. 8-13.

The even dash broken lines adjacent the claimed surfaces and dot dash broken lines represent the bounds of the claimed design while all other broken lines are directed to environmental structures and are for illustrative purposes only; the dot dash and even dashed broken lines form no part of the claimed design.
